UNITED STATES PATENT OFFICE.

WILLIAM FISH, OF EVERETT, MASSACHUSETTS.

TOOL FOR DRESSING EMERY-WHEELS.

No. 834,666.

Specification of Letters Patent.

Patented Oct. 30, 1906.

Application filed October 5, 1905. Serial No. 281,514.

To all whom it may concern:

Be it known that I, WILLIAM FISH, a citizen of the United States, residing at the city of Everett, in the county of Middlesex 5 and State of Massachusetts, have invented a new and useful Improved Tool for Dressing Emery-Wheels, of which the following is a specification.

This improved tool for dressing emery-wheels in substance is composed of a shank or handle of suitable length continued at one end in a stirrup, a wheel of alundum, emery, or of other suitable material for the dressing of an emery-wheel and which is located between the legs or branches of the stirrup and is hung on an arbor crossing between and attached to the stirrup-legs and so as to be free to rotate, but confined against lateral movement on said arbor, and of angular or shouldered rests, one on each leg of the stirrup and arranged to be, respectively, at different distances from, but in planes substantially parallel with, the axial line of the dressing-wheel, and so thereby when the tool 25 is placed by its said rests upon the edge of the rest of a lathe its said dressing-wheel will be presented in an angular direction relative to and across the width of the emery-wheel to be dressed and which has been suitably 30 located therefor on the spindle or arbor of the lathe, and all otherwise substantially as hereinafter described.

In the accompanying plate of drawings, forming a part of this specification, an improved tool of this invention is illustrated.

Figure 1 is in part a plan view and in part a horizontal section. Fig. 2 is an elevation at one side. Fig. 3 is a cross-section on line 3 3, Figs 1 and 2. Fig. 4 is a similar 40 view to Fig. 3, but showing the tool in its position for work and by dotted lines the then relative locations of the supporting edge of the lathe-rest, the axis of the lathe-spindle or arbor, and the vertical central plane of the 45 wheel to be dressed.

In the drawings, *a* is the handle or shank of any convenient length; *b* is the stirrup at one end and in continuation of the handle *a*; *c* is the dressing-wheel; *d* is the arbor of the 50 wheel *c*, and *ff* are the angular or shouldered rests of the stirrup *b*. The handle *a* and its stirrup end *b* may be in one continuous piece of metal or of other suitable material, and the dressing-wheel *c*, which may be of alundum, emery, or of any other suitable material, 55 is located between the parallel side legs

or branches of the stirrup, and across from one to the other of these arms the arbor *d* extends and at one end screws into one of the stirrup-arms and at the other end it is entered into a socket *g* of the other stirrup-arm, and between the two arms it is surrounded by a concentric sleeve *h*, having at one end a collar *i* and at the other end portion *j*, exteriorly screw-threaded and receiving a washer *k* and a screw-nut *l*. The dressing-wheel on the arbor through this interposed sleeve *h*, which is rigidly fastened to the wheel by screwing up the screw-nut *l*, turns or rotates on the arbor, but is confined 60 against lateral movement between the stirrup-arm by the screw-nut at one part and the sleeve-collar at the opposite part. *m* is a hole leading through the arm of the stirrup, which has the socket *g* receiving one end of 70 the arbor, and this hole is for introducing lubricating-oil to the arbor of the wheel.

Each branch of the stirrup has a similar leg extension *n*, and each extension has a similar right-angular-shaped rest, these rests 80 having their resting-faces *f*² located at different distances from the axial line of the dressing-wheel and both faces *f*² are in parallel planes and also planes parallel to the axis of the dressing-wheel, and their other faces 85 *f*³ are at right angles to their faces *f*². When the tool is to be used, the wheel to be dressed is first properly placed on the arbor or spindle of the lathe *a* and the dressing-wheel of the tool is presented to the peripheral 90 edge or surface of the emery-wheel by resting it, through the face *f*² of its shouldered rests *f*, on the edge of the lathe-rest and with the other edges *f*³ against the front face of the lathe-rest, and as the tool-rests are at different 95 distances from the axial line of the dressing-wheel, as described, obviously the periphery or working face of the dressing-wheel is angularly presented to the periphery or edge of the emery-wheel which is to 100 be dressed, substantially as shown by Fig. 4, in which the dotted line *p* represents the run of the supporting edge of the lathe-rest, (not shown), the dotted line *q* the axial line of the lathe arbor or spindle, (not shown,) and 105 the dotted line *r* a vertical plane through the wheel to be dressed running parallel to its end faces.

Alundum, the material herein referred to, and which is the most preferable material to 110 use, is an abrasive material manufactured from a raw material known as "bauxite," and

which is an amorphous hydrate of aluminium transformed into a pure crystalline abrasive in electric furnaces by a process patented in this and foreign countries.

5 Having thus described my invention, what I claim, and desire to secure by Letters Patent, is—

A tool for dressing emery-wheels, comprising a handle *a*, having a stirrup-shaped end *b*, and arbor *d* extending between and rigidly confined in the opposite branches or arms of said stirrup end *b*, a sleeve *h* free to rotate but confined against lengthwise movement on said arbor, a dressing-wheel *c* confined on said sleeve *h* and rotating therewith,

and a leg extension *n* on each branch of said stirrup end *b* and each of which leg extensions has two similar resting-faces *f²* and *f³*, with the resting-faces *f²* at different distances from, but both in parallel planes and also in planes parallel to the axis of said dressing-wheel, and with both resting-faces *f², f³*, of each at right angles to each other. 20

In witness whereof I have hereunto set my hand in the presence of two subscribing witnesses. 25

WILLIAM FISH.
